UNITED STATES PATENT OFFICE.

WILLIAM J. INNIS, OF OIL CITY, PENNSYLVANIA.

PULLEY.

SPECIFICATION forming part of Letters Patent No. 285,817, dated October 2, 1883.

Application filed August 18, 1883. (No model.)

To all whom it may concern:

Be it known that I, WILLIAM J. INNIS, a citizen of the United States, residing at Oil City, in the county of Venango and State of Pennsylvania, have invented certain new and useful Improvements in Pulleys, of which the following is a specification, reference being had therein to the accompanying drawings, in which—

10 Figure 1 is a vertical section; Fig. 2, a side elevation, and Figs. 3, 4, and 5 are vertical sections, showing modifications of a pulley constructed in accordance with my invention.

My invention relates to band-pulleys, and is 15 also applicable to other wheels, the object being to construct such pulleys and wheels of wood disks, made of two or more thicknesses of veneer or thin planks, a wood rim, and a cast hub, so that they shall be strong and light at 20 the same time; and my invention consists in certain features of construction, hereinafter described, and specifically pointed out in the claims.

Similar letters refer to similar parts throughout the several views.

The hub A consists of a casting suitably bored to fit a shaft upon the periphery of the hub, and cast integral therewith are one or two circular flanges, a, having one of their 30 faces dressed radially to receive the inner edge or circumference of the eye of the disk B. These disks are made of two or more thicknesses of veneer or thin boards glued together with their grain crossing each other. They 35 are pressed between forms, or in such a manner as to take and retain a concavo-convex or dished form; but their inner and outer edges are preferably set at right angles to the axis of the hub and parallel to each other, to facilitate their attachment to the hub and to the rim of the wheel.

The disks B are secured to the circular flanges a of the hub by means of clamping-rings a' and bolts or rivets b. After being 45 thus secured, the rim C is secured to the disk's outer edge. The rim is formed either of transverse laggings c, as shown in Figs. 1, 2, and 3, united together by means of nails or pins

c², passing in a tangential direction through one lagging and entering about half-way 50 into the other, or of segments glued or primed together, as shown in Fig. 4.

To unite the disks to the rim the latter is rabbeted on the inside, adjoining the edges thereof, as shown at c³, and preferably provided with grooves c⁴, to receive the edges of the disks. The central interior portion, c⁵, of the rim is thus made to enter and be received between the two disks of the pulley, to which it can then be glued, or to conveniently receive nails 60 or screws c⁶, driven into the outer edges of said disks, to unite them securely to the rim.

Two disks extending from the rim to the double-flanged hub may be used, as shown in Fig. 1, to construct the pulley; but pulleys 65 may also have their hubs provided with a single central flange and one of its wood disks, as shown at B', Fig. 3, may not extend to the hub thereof, but be riveted, glued, or nailed, as at b, to the disk that extends from hub to 70 rim.

Although the invention relates mainly to pulleys having wood disks made of two or more thicknesses of wood veneer and wood rim, it is closely related to pulleys having a 75 wood rim and metal disks, (shown in Fig. 4,) or pulleys having a metal rim, c⁷, and metal disks. (Shown in Fig. 5 of the present application and also in another application now allowed.) The outer edge of one disk is represented as flanged and riveted to the rim, and the other provided with a band of angle-iron, b².

Having now fully described my invention, what I claim, is—

1. A pulley constructed with a cast hub, wood disks made of more than one thickness, and a wood rim.

2. A pulley having concavo-convex wood disks of more than one thickness of veneer or 90 light board cemented or united together, as described, in combination with a cast hub and wood rim, substantially as and for the purpose described.

3. A pulley having a concavo-convex wood 95 disk extending from the hub to the rim, and

a second wood disk having its outer edge secured to the rim, and its inner edge secured to the stem of the first disk, in combination with a cast hub and a rim, substantially as shown and described.

4. The combination of a cast hub, wood disks made of one or more thicknesses, and a wood rim provided with circular rabbets or grooves to receive the outer edge of the disks,

substantially as and for the purpose described.

In testimony whereof I affix my signature in presence of two witnesses.

WILLIAM J. INNIS.
